United States Patent Office

Des. 185,822
Patented Aug. 4, 1959

185,822

SAILBOAT

George E. Hall, El Monte, and Sterling Osmon,
Santa Ana, Calif.

Application November 21, 1958, Serial No. 53,470

Term of patent 14 years

(Cl. D71—1)

FIG. 1

FIG. 2

FIG. 3

Figure 1 is a side elevational view of a sailboat embodying our new design, and the side of the boat opposite that shown in Figure 1 is substantially the same in appearance as the side shown;

Figure 4 is a rear view thereof and the mast and sail are broken away for convenience of illustration.

We claim:

The ornamental design for a sailboat, as shown and described.
